BALANCING TOY

Alfred J. Rosenfeld, East Cleveland, Ohio
(1516 Eddington Road, Cleveland, Ohio)

Filed Oct. 19, 1960, Ser. No. 62,533

Term of patent 14 years

(Cl. D34—15)

FIG. 1

The dominant feature of my design resides in the portion shown in full lines.

I claim:

The ornamental design for a balancing toy, as shown and described.
